UNITED STATES PATENT OFFICE.

WILLIAM SHARA, OF BROOKLYN, NEW YORK.

SAFETY LOCKING DEVICE FOR AUTOMOBILES.

Application filed April 5, 1922. Serial No. 549,893.

To all whom it may concern:

Be it known that I, WILLIAM SHARA, a citizen of the United States, residing at Brooklyn, in the county of Kings and State 5 of New York, have invented certain new and useful Improvements in Safety Locking Devices for Automobiles, of which the following is a specification.

This invention relates to safety locking 10 mechanism for automobiles, an object thereof being to provide an improved means of this character for locking the engine controls of the machine such as the switches for the self-starter, battery, or magneto, and 15 also for actuating an alarm or signal device upon unauthorized attempts to unlock the controls and start the machine.

A further object of this invention is to provide a combination tumbler locking mechanism 20 operative upon predetermined manipulation to lock and unlock the engine controls and switches, and also to actuate an alarm device upon erroneous manipulation of the combination tumblers by one unfamiliar with 25 the correct combination.

A further object of this invention is to provide an alarm device for automobiles operated automatically by a combination lock upon erroneous manipulation thereof, 30 such alarm device being disconnected by independent means and only when the control switches are operable.

A further object of the present invention is to provide an improved alarm device for 35 automobiles operated automatically by a combination lock upon erroneous manipulation thereof, the construction being such however that the alarm device may be disconnected only by correct manipulation of 40 the mechanism and the subsequent operation thereof to unlock the engine controls or switches.

Other objects of this invention will appear 45 in the following description thereof, reference being had to the accompanying drawings forming a part of this specification wherein like reference characters indicate corresponding parts in the several views and wherein Fig. 1 is an elevation view illustrating the installment of my improvement 50 on the dash-board of a vehicle, the casing being removed so as to clearly illustrate the various parts; Fig. 2 is a plan view thereof; Fig. 3 is a sectional view taken substantially 55 on lines 3—3 of Fig. 1; Fig. 4 is a plan view partly in section illustrating the mechanism;

Fig. 5 is a vertical section taken on lines 5—5 of Fig. 4; Fig. 5^a is a detail view illustrating particularly the position of the tooth sector when shifted to actuate the alarm; 60 Fig. 6 is a perspective detail view of certain of the parts of the locking mechanism; Figs. 7 and 8 are perspective views of certain of the tumblers of the combination lock; Fig. 9 is a bottom detail plan view of the contact 65 mechanism for the alarm device; and Fig. 10 is a detail perspective view illustrating the various parts of the contact mechanism for making and breaking the alarm circuit.

The present invention comprises in general 70 a combination lock having the usual tumblers and movable bolt cooperating therewith, an electrical switch adapted upon movement of the bolt to be locked and unlocked thereby, an electrically controlled 75 alarm or warning device, and a contact member adapted to be moved into position to complete a circuit through the alarm device by the movement of one of the tumblers of the combination lock. The construction of 80 the device is such however that after the alarm has once been actuated it cannot be disconnected except by obtaining the correct combination, unlocking the bolt and thereby causing the alarm circuit to be broken. 85

The present improved locking mechanism is preferably mounted upon the inside of the dash-board of the vehicle and of course it is understood that the same is suitably housed in a casing (not shown) so constructed as to 90 prevent unauthorized ingress thereinto. The major portion of the locking mechanism in the present instance is mounted in a supporting housing 9, bolted at 9^a to the rear of the dashboard. Within this supporting 95 housing 9 is located a combination lock of any preferred type comprising a knob 10 and a dial 10^a, and a plurality of revolving tumblers 11 mounted upon a spindle 12 which is suitably journaled in the housing 100 9. The several tumblers 11 are provided with the usual face studs 50 and notches 13 which upon obtaining the correct combination are adapted to be aligned with each other and receive the swinging bolt 14, pivoted at 105 15 to the opposite sides of the housing 9. The bolt 14 is provided with an upwardly extending projecting finger or dog 16 held in position between a stud 17 and a shoulder 18 of a shiftable locking latch 19. The forward portion of the latch 19 projects through 110 an opening in a guide member 20 secured to

the inner wall of the housing 9, this member 20 forming a guide for the forward portion of the latch. The rear end of the latch 19 is slotted as at 21 to receive the spindle 12 of the combination lock. Thus it will be readily seen that upon alining the several notches of the tumblers so as to permit the bolt 14 to fall thereinto, and upon turning the knob so as to swing the bolt downwardly or upwardly the latch 19 will be shifted in a horizontal path.

The forward end 22 of the latch is adapted to cooperate with the bent or right angle portion 23 of a lever 27 hereinafter described, which is pivoted at 23^a to the rear end of a link 24 for the control switches. In the present instance three switches are provided by way of example, the link 24 being pivoted directly to a switch 25 for the self-starter, and a switch 26 for the battery, and by means of the lever 27 connection is made to the switch 28 for the magneto. It will be understood of course that suitable wiring is provided so as to form the necessary circuits as is well known in the art, as generally indicated in Fig. 1. The link 24 is shifted for the purpose of controlling switches 25 and 26, and in like manner the lever 27 to control the switch 28 by means of a suitable handle 29 secured to a spindle 30 journalled in the housing 9 and having the squared shank portion 31 thereof fitting into a square hole in the lever 27. Thus upon turning the handle 29 in the proper direction the several switches will be swung into such positions as to complete the circuits to the magneto, starter and battery or to break the circuits when desired. Obviously when the forward end 22 of the latch 19 is in the locking position shown in Figs. 1 and 5, the several control switches will be firmly locked in position and in such position it will be impossible to turn the handle 29 and thus render it impossible to start the machine. However, upon unlocking the bolt 14 and shifting the latch 19 out of engagement with the portion 23, the switches may be readily operated by means of the handle 29.

In order to prevent any unauthorized operation of the engine, and to provide a warning when an attempt is made to start the engine by one unfamiliar with the combination, an alarm device 32 is provided, in the present instance in the form of a bell, the same being of any conventional construction. This alarm is controlled by the predetermined movement of the tumblers of the combination lock and after the alarm has been actuated it can be silenced only by unlocking and shifting the bolt 14. Projecting through the bottom of the housing 9 and suitably insulated therefrom is a binding post 33, the upper end thereof having a pair of arcuate members 34 reversely curved so as to form therebetween oppositely disposed

contact recesses. Above the contacts 34 is positioned swinging contact member 35 in the form of a toothed sector, the same being pivoted at 36 between the bifurcated ends 37 of a threaded rod 38. The rod 38 is screwed into the side of the housing or casing 9 and is grounded on the casing. The inner tumbler or disc 11^a of the combination lock which is fixed to the spindle 12 is provided with a projecting pin 39 so positioned that upon rotation of the tumbler 11^a the pin 39 will engage a tooth of the sector 35 and shift it one notch or step. It will be seen therefore that upon shifting the tumbler 11^a a sufficient number of turns all of the teeth of the sector 35 will be shifted step by step beyond the path of the pin 39, and at this time one of the outer teeth 40 or 43 will be moved into a contact recess of the contacts 34 thereby completing a circuit through the alarm. Rotation of the tumbler or disc 11^a in either direction will in this manner cause either tooth 40 or 43 of the sector 35 to be moved into one of the opposed recesses of the contacts 34. But, as soon as the pin 39 in its rotation has shifted all of the teeth of the sector 35 beyond its path and caused the alarm to be actuated, a reverse rotation of the tumbler 11^a will not disconnect the alarm for the reason that the pin 39, upon reversing, will not engage a tooth of the sector 35. This will be seen from a consideration of Fig. 5 and Fig. 5^a wherein the pin 39 moving in the direction of the arrow has shifted the tooth 40 to the position shown in Fig. 5^a. Upon reversing the direction of rotation of the tumbler the pin 39 will not engage tooth 40 but will pass freely thereover. Hence when the tooth sector 35 has been shifted to the position in Fig. 5^a thereby causing tooth 43 to engage contact 34 and actuate the alarm, movement of the tumbler in either direction will cause the pin 39 to pass freely over the tooth sector and fail to disconnect the alarm.

A suitable operator for the circuit breaker of the alarm device is provided in the form of a swinging lever 44 pivotally supported by means of a threaded stud 45 secured in the bottom of the casing 9. The lever 44 is insulated from the stud 45. This lever 44 is triangular in shape and the tapered end thereof projects between the sector 35 and the contact 34. The rear end of the lever 44 is cut away to provide stops 46 and 47 and a recess for receiving a depending finger 48 secured to the latch 19. Thus when the tooth sector 35 is swung in either direction to cause either tooth 40 or 43 to engage the contact 34, the forward end of the lever 44 will be swung laterally. As shown in Fig. 5, the bottom straight edge of sector 35 in normal position is in close proximity to the upper horizontal face of member 44 and projects at each side suf-

ficiently beyond the tapering edges of the member 44 so that when the sector is swung this bottom edge will engage the edge of member 44 and swing the member laterally.

5 When sector 35 is swung to the position in Fig. 5^a the outer tapered edge of tooth 43 also engages the edge of member 44 so that the latter will be swung into position to cause the projection 46 to engage the finger

10 48. Whereupon it will be seen that upon unlocking the bolt 14 and shifting the latch 19 to the left, the forward or tapered end of the lever 44 will be shifted to the right into its normal position shown in Fig. 5 thereby swinging sector 35 to its normal position and breaking the alarm circuit. On the other hand in case the sector 35 has been shifted so as to cause the tooth 40 to complete the alarm circuit through the con-

20 tact 34, the projection 47 will be moved to the left (see Fig. 6) into juxtaposition with the finger 48, and the projection 47, although engaging the lower end of a freely swinging latch 49, will pass thereover and 25 lodge in the space between the latch 49 and the finger 48. Hence upon unlocking the bolt 14 and shifting the latch 19 to the left the lower end of the latch 49 due to the spring 51 will be carried back over the projection 47 and lodged between the same and the finger 48. The alarm circuit can then be broken by shifting the tapered forward end of lever 44 to the left, this being accomplished merely by manipulating the 30 knob 10 and bolt 14 so as to shift the latch 19 to the right since the lower end of the latch 49 will engage the projection 47.

It will be understood that sector 35 may be provided with any suitable number of 40 teeth according to the number of turns in the combination. In the present instance where the combination requires not over four turns in either direction, the sector is provided with five teeth so that upon rotating the tumbler 11^a more than the required number of four turns, namely, five turns, the alarm will be actuated. In such case only the unlocking of the bolt 14 and shifting of latch 19 in the manner described 45 will operate the circuit breaker 44 to disconnect the alarm.

I claim as my invention:

1. A mechanism of the class described comprising a control switch, a combination lock comprising revolving tumblers, means automatically operated by said combination lock for controlling said switch, an alarm and means operated by said combination lock for operating said alarm only when a predetermined greater number of revolutions of the tumblers is made in one direction than in the other.

2. In a mechanism of the class described having a signal device, the combination of 60 a combination lock including a plurality

of rotatable tumblers, a swinging contact member, and means operated by a tumbler for swinging said contact member to close a circuit to said signal device only when a predetermined greater number of revolutions of the tumblers are made in one direction than in the other.

3. In a mechanism of the class described, the combination of an engine control switch, a combination lock comprising revolving 75 tumblers, means automatically operated by said combination lock for controlling said switch, a contact member for closing an alarm circuit, and means for progressively shifting said contact member in a predetermined direction to close the alarm circuit only when an excessive number of revolutions of the tumblers are made in a given direction.

4. In a mechanism of the class described 80 having a signal device, the combination of a combination lock including a rotatable tumbler, a pair of contact members for closing a circuit to said signal device, and means operated by said tumbler during the 85 rotation thereof for shifting one of said contact members into contact with the other only when a predetermined greater number of revolutions of the tumbler are made in one direction than in the other.

5. In a mechanism of the class described 90 having a signal device, the combination of an engine control switch, combination tumbler means, means operated thereby only when an excessive number of revolutions 95 thereof are made in one direction for closing a circuit to the signal device, and mechanism actuated by said tumbler means for breaking the circuit and including means for locking and unlocking said switch.

6. In a mechanism of the class described, the combination of a plurality of rotatable tumblers, a swinging bolt controlled by said tumblers, an engine control switch, a shiftable latch for locking said switch and connected to said bolt for operation thereby, a shiftable contact member for closing a signal circuit, means carried by one of said tumblers for operating the same, and means operated by said latch for shifting said contact member to break the signal circuit.

7. In a mechanism of the class described, the combination of a plurality of rotatable tumblers, a swinging bolt controlled by said tumblers, an engine control switch, a shiftable latch for locking said switch and connected to said bolt for operation thereby, a toothed sector forming a contact member for closing a signal circuit, and means carried by a tumbler for shifting said sector to close the circuit only upon making an excessive number of revolutions of the tumbler in one direction.

8. Mechanism of the class described comprising a plurality of tumblers, a movable 130

4
5 bolt controlled by said tumblers, an electric switch adapted to be locked and unlocked by said bolt, a pair of contact members for closing a signal circuit, one thereof shiftable toward and from the other and means carried by one of said tumblers for moving said shiftable contact member into engagement with the other contact member to close the signal circuit only when an excessive 10 number of revolutions of the tumblers are made in a given direction.

6 9. Mechanism of the class described comprising a plurality of tumblers, a movable bolt controlled by said tumblers, an electrical switch adapted to be locked and unlocked by said bolt, a pair of contact members for closing a signal circuit, means operated by one of said tumblers for moving one of said contact members progressively 15 into contact with the other member when an excessive number of revolutions of the tumblers are made in a given direction, and means operated by said bolt for breaking the circuit.

7 10. In a mechanism of the class described having an alarm device, the combination of a plurality of tumblers, a movable bolt controlled thereby, an electrical switch, a shiftable locking member adapted to be connected to said bolt and effective to lock and unlock said switch, a contact member for closing an alarm circuit, means operated by one of said tumblers for moving said contact member to close the circuit when an excessive number of revolutions of the tumblers are made in a given direction, and means for breaking the circuit only by shifting said locking member in a predetermined manner.

8 11. In a mechanism of the class described having a signal device, the combination of a plurality of rotatable tumblers, a shiftable contact member, means operated by a tumbler for shifting said contact member upon each rotative movement of the tumbler to cause said member to close a circuit to the signal device upon excessive rotation of the tumbler in a given direction, and means for shifting said contact member to break the circuit upon rotating said tumblers into proper combination.

9 12. Mechanism of the class described comprising an electrical control switch for an internal combustion engine, a combination lock including a plurality of tumblers and a bolt adapted to cooperate therewith, means operated by said combination lock for locking and unlocking said switch, a shiftable contact member, means operated by a tumbler for shifting said contact member to close a signal circuit, and means operated by

said bolt for shifting said contact member to break the circuit.

10 13. Mechanism of the class described comprising an electrical control switch for internal combustion engines, a combination lock including a bolt and tumblers, a shiftable latch adapted to be operated by said bolt for locking and unlocking the switch, a contact member, means carried by a tumbler 70 for shifting the contact member in one direction to close a signal circuit when a predetermined greater number of revolutions of the tumblers are made in one direction than the other, and a member operated by 75 said bolt for breaking the circuit.

11 14. Mechanism of the class described comprising an electrical control switch for internal combustion engines, a combination lock including a bolt and tumblers, a shift- 80 able latch adapted to be operated by said bolt for locking and unlocking the switch, a contact, a toothed member, means operated by a tumbler when an excessive number of revolutions of the tumblers are made in a 85 given direction for shifting said toothed member into engagement with said contact to close an alarm circuit, and a member actuated by said latch for breaking the circuit.

12 15. Mechanism of the class described comprising an electrical control switch for internal combustion engines, a combination lock including a bolt and tumblers, a shiftable latch adapted to be operated by said bolt for locking and unlocking the switch, a 90 contact, a movable contact member adapted to be shifted by one of said tumblers into contact with said contact to close an alarm circuit when an excessive number of revolutions of the tumblers are made in one direction, and a member actuated by said latch for breaking the circuit. 100

13 16. In an automobile locking mechanism, the combination of a contact, a combination lock comprising rotatable tumblers, one of said tumblers having a projection, and a 110 shiftable member having teeth adapted to be successively engaged by said projection upon each predetermined revolution of said tumbler, the teeth of said member being shifted out of engagement with said projection when 115 an excessive number of revolutions of the tumblers are made in a given direction to cause said member to engage said contact.

Signed at 1822-3-4 Park Row Bldg., N. Y. City, this 1st day of April 1922.

WILLIAM SHARA.
